Primary Examiner—Ruth McInroy*Attorney, Agent, or Firm*—Wolf, Greenfield & Sacks, P.C.[57] **CLAIM**

The ornamental design for an antenna cover, as shown and described.

DESCRIPTION

FIG. 1 is a front, elevational view of an antenna cover showing my new design, the rear view being identical; FIG. 2 is a right side elevational view thereof, the left side being identical;

FIG. 3 is a bottom plan view thereof; and,

FIG. 4 is a top plan view thereof.

The details shown in broken lines in all views are shown for illustrative purposes only and form no part of the claimed design.
